UNITED STATES PATENT OFFICE.

FRANK A. WARTER, OF WOODBRIDGE, NEW JERSEY, ASSIGNOR OF ONE-HALF TO
CHARLES ANNESS, OF WOODBRIDGE, NEW JERSEY.

VALVE.

Application filed December 28, 1921. Serial No. 525,296.

To all whom it may concern:

Be it known that I, FRANK A. WARTER, a citizen of the United States, and a resident of Woodbridge, county of Middlesex, and State of New Jersey, have invented certain new and useful Improvements in Valves, of which the following is a specification.

This invention relates to an improved valve which is adapted for different uses, but in order to make the invention clear is described herein as applied to a valve used in acid and similar pipe lines.

The object of the invention is to provide a valve which has the face which engages the seat constructed so that the valve takes up inequalities due to the improper machining or aligning of the seat or stem, and the valve is thus enabled to remove strain from these parts in any attempt to force it shut and also to make a complete closure.

The invention is illustrated in the accompanying drawing, in which Figure 1 is a section, partly in elevation, of a valve embodying my invention. Figure 2 is a detail view 25 of the valve parts shown in Figure 1, separated, one part being shown in section. Figure 3 is a sectional view of a modified form of valve.

So far as the main parts of the valve illustrated are concerned, they are not new, as I show a conventional valve casing 10 with the passage 11 through it and a bonnet 12 in which the stem 13 slides, being actuated by suitable means, such as the hand wheel 14 on the head 15.

The bonnet and the part 10 in acid valves are made of or lined with lead or similar acid-resisting material, and the valve casing has a valve seat 16 which is adapted to be closed by the valve on the end of the stem.

That face of the valve that engages the seat 16 can be made as in Figures 1 and 2, in which I show a lead ring 17 of tubular form which is secured, by burning, on the end of the lead head 18, which is the extension of the covering 19 of the stem 13. When the tube is burned on, lead is accumulated around the tubular part 17 and within the space enclosed thereby to give it good stability and adherence to the head 18, as shown in Figure 1, but leaving the lower edge comparatively thin. This structure forms an air chamber or cushion 20. The head 18 and the tube 17, when put together as shown in Figure 1, form a one-piece or integral struc-

ture, the additional lead that is burned on when the parts are assembled forming not only a backing for the tube 17 by strengthening the back part, but also making a substantial and solid fastening means so that the two separated elements shown in Figure 2 form the integral structure shown in Figure 1.

It will be readily seen that when the valve parts are assembled, any inequality of alignment of the valve stem, or improper machining of the parts, or any improper facing or lining of the valve seat or valve stem that causes the valve 17 to be improperly seated on the valve seat at first contact, is compensated for by the cushioning of the valve.

The somewhat flexible ring 17 is compressed at the points of first contact, and a uniform tight seat is provided. The air cushion inside the ring 17 allows the compression of the valve, and since the thin walls of the part 17 are usually made of softer metal than the valve seat, the seat is not injured or unevenly worn. A new valve and stem can be readily installed without regrinding the valve when an old one is worn out, as it is not necessary to machine the body of the valve and its valve seat. In fact, it is not necessary to do any machining whatever on the insertion of a new valve and stem as the initial seating of the valve will cause it to conform to the seat.

In Figure 3 I show a modified form of valve in which a soft flexible cushion disk or block 21 of leather, rubber, asbestos or similar resilient material is placed in the end of the cover of the valve stem and is covered on the outside by a thin, somewhat flexible sheet 22 of sheet lead so as to form an integral part of the lead valve head for use in chemical solution processes where liquid, fumes, vacuum or vapor of corrosive nature are conducted. The cushion 21 is of sufficient flexibility to compensate for indenting or distorting the face 22 of the valve.

I claim:

1. A valve comprising a casing having a seat therein, a valve to close the seat, a stem for the valve, the valve comprising a single piece of lead enclosing the stem and formed beyond the stem with a hollow portion, the walls of which are of sufficient thinness to permit of slight distortion.

2. A valve comprising a casing having a seat therein, a valve to close the seat, said

valve having a one-piece head with a closed space arranged in said head near its contacting face, and a cushion material in said portion.

5 3. A valve comprising a casing having a seat therein, a valve to close the seat, said valve having a one-piece hollow head with a

thin outer end, and a cushioning block in said head and protected thereby from fluid passing through the valve.

In testimony that I claim the foregoing, I have hereto set my hand, this 24th day of December, 1921.

F. A. WARTER.
